CLAIM

The ornamental design for a hinge, as shown and described.

DESCRIPTION

FIG. 1 is a top and front perspective view of part A of the hinge, showing half of my new design;

FIG. 2 is a rear perspective view of part A of the design illustrated in FIG. 1;

FIG. 3 is a front view of part A of the design illustrated in FIG. 1;

FIG. 4 is a top plan view of part B of the hinge, showing the other half of my new design;

FIG. 5 is a front view of part B of the design;

FIG. 6 is a rear perspective view of part B of the design;

FIG. 7 is a top and front perspective view of part B of the design;

FIG. 8 is a top plan view of the design assembly with parts A and B assembled in a straight configuration;

FIG. 9 is a front view of the design assembly with parts A and B assembled in a straight configuration;

FIG. 10 is a right side view of the design assembly with parts A and B assembled in a straight configuration, the left side view being a mirror image thereof;

FIG. 11 is a top and front perspective view of the design assembly with parts A and B assembled in a bent configuration;

FIG. 12 is a rear perspective view of the design assembly with parts A and B being assembled; and,

FIG. 13 is a rear perspective view of the design assembly with parts A and B assembled in a straight configuration.
